UNITED STATES PATENT OFFICE.

JOSEPH H. ALLEN, OF CHICAGO, ILLINOIS, ASSIGNOR TO INLAND GLASS COMPANY, OF CHICAGO, ILLINOIS, A CORPORATION OF ILLINOIS.

DISPENSING APPARATUS FOR LIQUID HYDROCARBONS.

Application filed November 19, 1925. Serial No. 69,986.

My invention relates to oil dispensing apparatus, such for example, as are used in "gas filling stations" where motor vehicles are supplied with motor fuel. It has been 5 common practice heretofore to employ transparent containers so that the purchaser of gasoline would be able to see what is being measured out to him. The walls of these containers have consisted of open-ended glass cylinders, the ends of which are closed by covers or plates of various design clamped under pressure to the end of the cylinder with gaskets intervening to prevent leakage. These cylinders are usually about 10 24 inches in diameter, and at the ends the glass is ground so as to make a smooth and true finish. The fact is, however, that grinding the edge of a sheet or cylinder of glass is very much like nicking it, for the 15 glass is weakened, and experience has shown that a considerable percentage of these glass cylinders used at filling stations crack when subjected to the degree of clamping pressure which is necessary to prevent leakage past 20 the lower end of the cylinder. These glass cylinders are somewhat expensive, but the greatest disadvantage is the danger which attends the breaking of a cylinder when 25 filled with gasoline. Such cylinders are usually mounted approximately as high as a man's head or higher, and the result is that if the cylinder breaks it is apt to deluge a bystander, and fires have frequently resulted 30 from the sudden and unexpected flow of gasoline. These accidents cannot well be 35 avoided because it requires a certain minimum pressure per linear unit of glass edge to seal the joint against leakage, and furthermore it is difficult in tightening up the 40 clamping rods to produce a uniform pressure throughout the periphery, and one which shall not be excessive at any one point. In other words, it is difficult to prevent 45 excessive and unequal strains on these open-ended cylinders, and this is another factor which contributes to the percentage of breakages. The object of my invention is to provide in apparatus of this class a glass container which will greatly reduce the liability 50 of breakage.

I obtain my objects by the construction illustrated in the accompanying drawings in which

Figure 1 is an assembly view showing the apparatus chiefly in diametrical vertical section. 55

Figure 2 is a side elevation of the apparatus viewed at right angles to the direction in Figure 1, a portion of the wide wall and stand pipes being broken away to reveal the 60 internal arrangement.

Figure 3 is a plan section taken on the line 3—3 Figure 1.

Like numerals denote like parts throughout the several views. 65

According to the design selected to illustrate the invention there is a base frame or casting 10 supported by legs 12 or otherwise from a foundation 14 of any suitable type. This casting has an outlet duct 16 through 70 which the liquid may be drawn off. In the particular connection illustrated, duct 16 communicates with a nipple 18 leading to an elbow 20 to which the delivery hose 22 is attached. It will be understood that these 75 features may be greatly varied without departing from the spirit of the invention.

Near the center, the base frame 10 has screw threaded bosses 24 which form couplings for connecting pipes 26 which extend 80 below the apparatus to pipes 28 which project up into the container. One of these pipes 28 is a filler pipe and the other an overflow. It will be understood that the number and functions of these internal pipes 85 may be varied to suit requirements.

On its upper surface the base frame 10 has an insulating surface 30 for supporting a gasket 32. It also has a channel 34 for supporting an outer gasket 36. 90

The container 38, instead of being a plain, open-ended cylinder more nearly approximates an inverted bottle. It is closed at the top and at the bottom is closed for about half its diameter, the central opening being surrounded by a short annular flange 40. This flange rests upon the gasket 32, and the shoulder of the container rests upon the gasket 36. The gasket 32 should be 95 made of a material which will not be readily 100

- affected by gasoline or similar hydro-carbon, whereas the gasket 36 should be of rubber or similar resilient material which will cushion the container, thus permitting a limited vertical adjustment and also absorbing the ordinary shocks and jars which may be created in various ways, for example, by loaded motor trucks in the vicinity of the apparatus.
- 10 The container is clamped down onto the base frame 10, for instance by a spider 42 and clamping bolts 44, which pass down through the spider and through the base frame. Pads 46 are desirable between the 15 arms of the spider and the inner surface of the container to cushion the clamping arms and distribute the strains over the glass. It will be noted that in the particular arrangement illustrated the pads are approximately 20 back of the flange 40 and thus the thrust of the pads is absorbed by that portion of the container which is reinforced by the flange. In other words, the pads are applied near the point where the container is reinforced.
- 25 According to the illustrated design, the base frame 10 has an upstanding peripheral flange 48 which surrounds the lower end of the container and prevents it from being laterally displaced. This flange also carries 30 apertured lugs or eyes 52 which accommodate rods 54. These rods serve the dual function of protecting the glass from contact with external objects and they also serve to clamp down the cover 54. This cover overlies the 35 container and is held down by the rods 54 which screw into it. A gasket 56 intervenes between the cover and the top of the container to produce a cushioning effect and distribute the strains.
- 40 As a result of my invention the liability of failure of the apparatus is reduced to a minimum. As the top of the container is closed there is no ground upper edge to cause 45 weakness. The top of the container, on the contrary, forms a wall for bracing and strengthening the sides of the container, as in an ordinary bottle or demijohn. The same is true at the bottom of the container except that here there is a central opening of 50 reduced diameter. This opening, however, is reinforced by the flange 40 and the danger of breakage is reduced in proportion. Furthermore the aggregate pressure required in order to prevent leakage at the gasket 32 is 55 very much less than if this gasket were in line with the outer walls of the container. If the diameter of the central opening is only half as great as the diameter of the outer walls of the container, it follows that 60 the perimeter of flange 40 is only half as long as the perimeter of the outer walls. The result is that the aggregate pressure is reduced one-half. All other things being

equal, a definite pressure per running inch is required to prevent leakage, and of course 65 if the perimeter is reduced, the aggregate pressure will be proportionately reduced. As a result, the aggregate pressure in my apparatus is much less than with the previously used open-ended cylinders. Furthermore 70 this pressure is exerted over a very much smaller circle and hence the danger resulting from unequal clamping stresses is correspondingly reduced.

It will also be noted that in my apparatus 75 the clamping pressure for preventing leakage does not come from the cover 55, which presses upon the top of the container, but chiefly from the spider 42 which is located inside of and at the bottom of the container. 80 The tie rods or clamping rods 54 and the cover 55 serve chiefly to protect the sides and top of the glass from being struck by external objects, and to assist in holding the container in place. These rods and the cover 85 might, however, be dispensed with, for the container rests jointly upon the gasket 32 and gasket 36, and is clamped down in position by the spider 42 and hence under certain conditions the rods and cover would not 90 be required.

It will also be observed that as my apparatus in its illustrated form contains two pairs of clamps, viz the cover 55 cooperating with the supporting frame, and the spider 95 42 cooperating with said frame, and as the clamps are applied at different distances from the central axis of the container, it is evident that the pressure necessary to prevent leakage and to support the container will be 100 more effectively distributed than if there were but one clamp as in the old construction, with the pressure applied only at the outer wall of the container.

While I have shown the glass container in a form in which the top is entirely closed by glass it will be understood that it is not 105 essential that the top be imperforate. A small aperture might be formed in the top without departing from the spirit of the invention provided that the top of the container extends inward for a considerable distance, thus making either a continuous top or a flange at the top which will avoid the need of grinding the ends of the cylinder. 110 It will also be understood that while my apparatus is intended primarily for the dispensing of liquids it may be otherwise used. For example by creating a vacuum within 115 the container the apparatus may be used for drawing off the old oil from the crank case of a car.

Having thus described my invention what I claim as new and desire to secure by Letters Patent is:

Apparatus for dispensing liquid consisting

of a glass container approximately in the form of a cylinder having glass extending inward at the top and having a constricted opening at the bottom, a support for the container having a plurality of openings for the passage of liquid, a spider located within the container and adapted to bear upon the constricted portion thereof, and means for clamping the support and spider toward each other to prevent leakage from between them. ¹⁰
In witness whereof, I have hereunto subscribed my name.

JOSEPH H. ALLEN.
